[57] CLAIM

The ornamental design for a speculum, as shown and
described.

DESCRIPTION

FIG. 1 is a perspective view looking toward one end
and one side of a speculum, showing my new design.
FIG. 2 is an elevational view thereof looking from the
right side in FIG. 1.

FIG. 3 is an elevational view thereof looking from the
left side in FIG. 1.

FIG. 4 is a perspective view looking toward the end
and side thereof opposite those shown in FIG. 1.
